Primary Examiner — Manpreet Matharu*Assistant Examiner* — Yolanda Robinson(74) *Attorney, Agent, or Firm* — Tuggle Duggins P.A.; Blake Hurt(57) **CLAIM**

The ornamental design for a debris capturing net, as shown and described.

DESCRIPTION

FIG. 1 is a top, front, right side perspective view of a debris capturing net showing my new design;

FIG. 2 is a top plan view thereof, the bottom plan view being a mirror image thereof;

FIG. 3 is a rear elevational view thereof;

FIG. 4 is a front elevational view thereof;

FIG. 5 is a left side elevational view thereof, the right side elevational view being a mirror image thereof; and,

FIG. 6 is an enlarged perspective view showing the closure portion of the debris capturing net.

The dashed lines shown in FIG. 1 are included for the purpose of illustrating environment and form no part of the claimed design.

1 Claim, 4 Drawing Sheets(56)
